DESIGN FOR A HAT

John C. Marks, New York, N. Y.

Application December 23, 1943, Serial No. 112,077

Term of patent 3½ years

To all whom it may concern:

Be it known that I, John C. Marks, a citizen of the United States of America, residing in New York city, county of New York, and State of New York, have invented a new, original, and ornamental Design for a Hat, of which the following is a specification, reference being had to the accompanying drawing, forming part thereof.

The figure on the drawing is a front perspec-

tive view of a hat showing my new design. The opposite view of the hat is substantially the same as the side shown.

The dominant feature of my design resides in the portion shown in solid lines.

I claim:

The ornamental design for a hat, substantially as shown and described.

JOHN C. MARKS.
